UNITED STATES PATENT OFFICE.

OTTO P. DOWNING, OF DALLAS, TEXAS.

DESIGN FOR A RUBBER TIRE.

48,885.

Specification for Design.

Patented Apr. 18, 1916.

Application filed February 8, 1916. Serial No. 77,018. Term of patent 14 years.

To all whom it may concern:

Be it known that I, OTTO P. DOWNING, a citizen of the United States, residing at Dallas, in the county of Dallas and State of Texas, have invented a certain new, original, and ornamental Design for Rubber Tires, of which the following is a specification, reference being had to the accompanying drawings, forming part hereof, in which—

Figure 1 is a perspective view of a rubber tire showing my new design; Fig. 2 is a side elevational view; and Fig. 3 is a top or plan view thereof.

I claim:—

The ornamental design for a rubber tire, as shown.

OTTO P. DOWNING.
